UNITED STATES PATENT OFFICE

2,250,350

RAZOR

Walter Berry, Greensboro, N. C.

Application September 12, 1940, Serial No. 356,526

6 Claims. (Cl. 30—43)

My invention relates to improvements in razors and its general object is to provide an electric razor wherein the cutting member comprises an elongated spiral, or a plurality of such spirals, positioned about the periphery of the surface of a cylindrical member journaled in a housing member.

A further object of my invention is to provide a razor of the character described wherein novel face guards are employed.

A still further object of my invention is to provide a razor of the character described wherein the movement of the cutting member serves to eject the cut hair from the chamber in the housing adjacent the cutting member.

With these and other objects in view, as will hereinafter more fully appear and which will be more particularly pointed out in the appended claims, reference is now made to the accompanying drawing forming a part of this application, in which—

Fig. 1 is an elevational view, partly broken away, showing my improved razor in its preferred form;

Fig. 2 is a side elevational view thereof;

Fig. 3 is a transverse, section view, on an enlarged scale, taken on the line 3—3 of Fig. 1;

Fig. 4 is a detail view, showing the cylinder and the preferred form of the spiral cutting member;

Fig. 5 is an end view of the cylinder and cutting member shown in Fig. 4;

Fig. 6 is a detail view, showing the preferred form of the face guard employed;

Fig. 7 is also a detail view, showing a modified form of face guard;

Fig. 8 is also a detail view, showing another modification of face guard;

Fig. 9 is an end view of a modified form of cylinder, wherein a plurality of spiral cutting members are employed; and

Fig. 10 is a side elevational view of the modification shown in Fig. 9.

Referring now to the drawing, in which similar reference characters represent similar parts, my improved razor comprises a housing 10, containing a conventional electric motor 12, provided with the usual switch 14. The motor 12 drives cylinder 16, through a conventional flexible cable 18 and gears 20 and 22. Cylinder 16 is journaled in the housing and is provided about the periphery of its surface with a cutting member 24, in the form of an elongated spiral. A U-shaped face guard 26 is fitted over the cylinder and cutting member and is secured to the

housing by means of conventional screws 28. The U-shaped face guard, in the preferred form shown in Figs. 1, 2, 3 and 6, is provided with two longitudinal, rectangular slots 30, through which the beard or hair is adapted to extend, where it is sheared off between the cutting member 24 and the edges of the slots. When the hair is cut off, it is pushed into the space 32 between the cylinder and the housing, under action 10 of the cylinder and spiral cutting member 24 and is ejected from the housing through opening 34. (See Figs. 1, 2 and 3.)

Referring now to the modification shown in Figs. 9 and 10, the cylinder 16a is provided with a plurality of spiral cutting members 24a.

Referring to the modification shown in Fig. 7, the face guard 26a is provided with a plurality of circular openings 30a, through which the beard or hair extends to be sheared off.

Referring to the modification shown in Fig. 8, the face guard 26b is provided with a plurality of longitudinal, rectangular openings 30b of varying lengths, the openings being staggered with reference to the adjoining row.

From the foregoing it will be apparent that the cutting or shearing of the beard or hair is accomplished in a far more effective manner than with other razors of this same general class, due to the fact that the cutting member or members passes over the slots or openings in the face guard at a wide angle, thereby causing an easier severance.

While I have illustrated and described the invention in some detail, it is to be understood that the invention is not to be limited to such details, but only by the spirit of the invention and the scope of the appended claims.

I claim:

1. A razor of the character described, comprising a housing, a U-shaped face guard attached to one end of the housing, a cylinder journaled in the housing between the U-shaped face guard sides, an elongated spiral cutting member carried by the cylinder, an opening in one side of the housing adjacent the end of the cylinder, power means carried by the housing for rotating the cylinder, and a plurality of openings in the face guard whereby the hair is sheared off between the edges of said openings and the cutting member.

2. A razor of the character described, comprising a housing, a U-shaped face guard attached to one end of the housing, a cylinder journaled in the housing and face guard, an elongated spiral cutting member carried by the cyl-

inder, an opening in one side of the housing adjacent the end of the cylinder, power means carried by the housing for rotating the cylinder, and a plurality of longitudinal, rectangular openings in the face guard parallel to the axis of the cylinder whereby the hair is sheared off between the edges of said openings and the cutting member.

3. A razor of the character described, comprising a housing, a U-shaped face guard attached to one end of the housing, a cylinder journaled to the housing within the face guard, a plurality of elongated spiral cutting members carried by the cylinder, an opening in one side of the housing adjacent the end of the cylinder, power means carried by the housing for rotating the cylinder, and a plurality of openings in the face guard whereby the hair is sheared off between the edges of said openings and the cutting member, the cutting member ejecting the sheared hair through the opening in the side of the housing.

4. A razor of the character described, comprising a housing, a U-shaped face guard attached to one end of the housing, a cylinder journaled in the housing and within the face guard, a plurality of elongated spiral cutting members carried by the cylinder, power means carried by the housing for rotating the cylinder, an opening in one side of the housing adjacent the end of the cylinder, and a plurality of openings in the face guard whereby the hair is sheared off between the edges of said openings

and the cutting members, the cutting members ejecting the sheared hair through the opening in the side of the housing.

5. A razor of the character described, comprising a housing, a U-shaped face guard attached to one end of the housing, a cylinder journaled in the housing and within the face guard, a plurality of elongated spiral cutting members carried by the cylinder, power means carried by the housing for rotating the cylinder, an opening in one side of the housing adjacent the end of the cylinder, and a plurality of longitudinal, rectangular openings in the face guard parallel to the axis of the cylinder whereby the hair is sheared off between the edges of said openings and the cutting members, the cutting members ejecting the sheared hair through the opening in the side of the housing.

6. A razor of the character described, comprising a housing, a U-shaped face guard attached to one end of the housing, a cylinder journaled in the housing and within the face guard, a plurality of elongated spiral cutting members carried by the cylinder, power means carried by the housing for rotating the cylinder, an opening in one side of the housing adjacent the end of the cylinder, and a plurality of circular openings in the face guard whereby the hair is sheared off between the edges of said openings and the cutting members, the cutting members ejecting the sheared hair through the opening in the side of the housing.

WALTER BERRY.
